INVENTOR,
BY James A. Wiles,
Howard S. Smith,
for ATTORNEY

UNITED STATES PATENT OFFICE

JAMES A. WILES, OF HAMILTON, OHIO

STORAGE BATTERY TERMINAL PULLER

Application filed March 18, 1929. Serial No. 347,864.

This invention relates to new and useful improvements in storage battery terminal pullers.

It is the principal object of my invention to provide for application to a corroded or other tight storage battery terminal, a screw device by which it may be easily removed.

The subject of this application differs from the terminal puller disclosed in my prior application Serial Number 264,812 now Patent No. 1,707,379, by being of more universal application.

In the accompanying drawing illustrating my invention, Figure 1 is a top plan view of my terminal puller applied to a late type of storage battery terminal. Figure 2 is a side view thereof. Figure 3 is an end view of the same. Figure 4 is a sectional view taken through the device on the line 4—4 of Figure 1. Figure 5 is a bottom plan view of my puller applied to a different type of terminal than that disclosed in the preceding figures. And Figure 6 is a top view of the assembled casting and wings, omitting the top plate, pressure screw and hooks.

Referring to the accompanying drawing for a detailed description of the form of embodiment of my invention disclosed therein, the numeral 1 designates a casting which is H-shaped in side view and has a cross portion 2 with a wide central part. Secured by screws 3, 3 to the tops of the legs of the H casting 1 is a cap plate 4 formed with a top rib 5 having a central screw hole which extends downwardly through the plate.

Mounted between the cap plate 4 and the middle part of the cross portion 2 and abutting against a hollow axial projection 6 on the latter, are two wing members 7, 7. Each wing member is formed with a tapering hole 8 which is of greatest diameter at the bottom to freely receive a swivel hook 9 having its upper end threaded. To the threaded end of each hook 9 a knurled cap nut 10 is applied. At its outer upper end each wing 7 is formed with a beveled crown portion adapted to engage the cap plate 4 and whose top surface is in the same horizontal plane

as the top of the plate for an even engagement by a respective cap nut 10.

Each wing 7 is formed with an end projection 7a which is received by an arcuate groove in the inner surface of the cap plate 4. This permits the wing to be easily shifted about the conical projection 6, which acts as rear stop for it, to a position where the hook 9 carried by the wing may best engage the terminal to be removed. The engagement of the projections 7a on the inner ends of the wings 7, in the arcuate grooves of the cap plate 4, prevents these wings from being pulled out when the cap nuts 10 are screwed down on them. (See Figure 4).

Formed in the central ribbed portion of the cap plate 4 is a screw hole which is directly over a similar hole which extends through the cross portion 2 of the casting 1.

Contained in the screw holes just referred to, is a screw or stud 11 formed with an outer wrench receiving head 12. On its inner end the screw 11 carries a swivel cap 13 to engage a post 14 of a storage battery 15.

Near its lower end each leg of the H casting 1 is formed with a downwardly inclined screw hole to receive a stud 16. By engaging from the sides a terminal such as that shown in Figure 5, the studs 16, 16 assist one of the hooks 9 in establishing a firm grip on the terminal when the latter is to be pulled from a post 14.

Preparation for the pulling of a terminal such as that shown in Figures 1 to 4 inclusive, is made by fitting the central hole in the cross portion 2 of the casting 1 over the battery post 14 upon which this terminal, which will be designated by the numeral 17, has corroded. The hooks 9, 9 are then drawn tightly into engagement with the cable receiving and clamping portions of the terminal by the cap nuts 10, as shown in Figure 2, and the studs 16, 16 screwed into engagement with its middle portion. The screw 11 is then turned to engage the top of the post, whereupon the casting 1 will be elevated by the screw to pull the terminal from the post through the instrumentality of the hooks 9 and studs 16.

If a terminal such as that shown in Figure

5 is to be pulled, the casting 1 is placed over its post 14 as before described. The studs 16, 16 are then screwed against the terminal, which will be designated 18, and one of the 10 hooks 9 applied to the clamping portion of the latter. The hook 9 is then drawn into tight engagement with the terminal by the cap nut 10. When the screw 11 is then turned against the post 14, the terminal 18 15 will be pulled from it with ease by one of the hooks 9 and both of the studs 16.

It will thus be seen that my improved terminal puller may be applied to terminals of the latest types to remove them with ease 15 from the posts of the storage batteries receiving them.

Having described my invention, I claim:

1. A device of the type described for pulling a terminal from a storage battery post, 20 comprising a screw holding member, a top on said member formed with arcuate grooves in its inner surface, said screw holding member and top being formed with oppositely disposed screw holes, a screw in said holes 25 adapted to engage said post, wing members having inner ends shaped to travel in said grooves, and means carried by said wing members for removably engaging said terminal to pull it from the post when the pressure of the screw is applied to the latter.

2. A device of the type described for pulling a terminal from a storage battery post, comprising a screw holding member, a top on said member formed with arcuate grooves in 35 its inner surface, said screw holding member and top being formed with oppositely disposed screw holes, a screw in said holes adapted to engage said post, wing members having inner ends shaped to travel in said grooves, a 40 hollow axial projection on the screw holding member through which the screw passes and which is engaged by the rear ends of the wing members in any of their adjusted positions, and means carried by said wing members for 45 removably engaging said terminal to pull it from the post when the pressure of the screw is applied to the latter.

3. A device of the type described for pulling a terminal from a storage battery post, 50 comprising a screw holding member formed with a central screw hole, a screw in said hole adapted to engage said post, legs on said member adapted to straddle said terminal, and studs passing through said legs for engagement with said terminal to pull it from the post when the pressure of the screw is applied to the latter.

4. A device of the type described for pulling a terminal from a storage battery post, 60 comprising a screw holding member formed with a central screw hole, a screw in said hole adapted to engage said post, legs on said member adapted to straddle said terminal, a hook swiveled to said casting for removable engagement with said terminal, and studs

passing through said legs for engagement with said terminal to assist the hook in pulling it from the post when the pressure of the screw is applied to the latter.

5. A device of the type described for pulling a terminal from a storage battery post, 70 comprising an H shaped casting, a top plate on the latter formed with a central screw hole, the cross portion of the casting formed with a screw hole below the first screw hole, 75 a screw passing through both holes to engage said post, wing members shiftably secured between the cross portion of said casting and said top plate, hooks carried by said wing members for removable engagement with said terminal, and studs passing through the lower ends of the leg portions of the H shaped casting for engagement with said terminal for the purpose specified.

6. A device of the type described for pulling a terminal from a storage battery post, 80 comprising a screw holding member formed with a central screw hole, a screw in said hole adapted to engage said post, shiftable wing members projecting from the sides of the 85 screw holding member, arcuate guiding and holding means on the screw holding member for the wings, arcuate means on the wings co-operating with said guiding and holding means, and hooks carried by said wing members for removably engaging said terminal to pull it from the post when the pressure of the screw is applied to the latter.

In witness whereof I have hereunto set my hand this 16 day of March, 1929.

JAMES A. WILES.
